UNITED STATES PATENT OFFICE.

HENRY ROGERS MASSINGHAM, OF LA GRANGE, ILLINOIS, ASSIGNOR TO WESTERN ELECTRIC COMPANY, INCORPORATED, OF NEW YORK, N. Y., A CORPORATION OF NEW YORK.

METHOD OF AND APPARATUS FOR SERVING MATERIAL TO A CORE.

Application filed October 19, 1926. Serial No. 142,624.

This invention relates to methods of and apparatus for serving material to a core, and more particularly to a method of and apparatus for serving strand material to a non-circular shaped core.

It is the practice in connection with the manufacture of certain types of electrical cables, principally those employed for interconnecting sections of telephone
10 change switchboards, to form the cable by helically serving a plurality of twisted pairs of wires on a non-circular core of flat pressboard. It will be apparent as any particular pair of wires is wrapped around
15 either narrow edge of the core that the rate of speed at which the pair of wires is withdrawn from its supply source will be increased suddenly as it is laid across either of the wide flat surfaces of the core, and
20 upon being wrapped around the core at either edge thereof the rate of their withdrawal will be decreased suddenly. Due to the intermittent, irregular or jerky speed at which the wires are being withdrawn
25 from their supply sources, extreme care must be taken in the stranding of flat, elliptical or other non-circular shaped cable, in that due to the inertia of the supply spools, breakage in the wires or the cutting of the
30 core at the edges thereof may occur.

The object of this invention is to provide a method of and apparatus for eliminating any tendency of the strand material to distort the core by deleterious strains or pressures thereon or otherwise during the serving thereof to cores of a non-circular type which results in the production of a product which is of a substantially uniform cross-section over its entire length.

40 In order to attain this object in accordance with one embodiment of this invention, as practiced in connection with the forming of a flat type telephone switchboard cable wherein the core comprises a
45 thin flat strip of pressboard, a plurality of strands or wires are withdrawn from a plurality of supply spools and distributed uniformly around the longitudinal axis of the core. During the travel of the strands or wires from the point of distribution to the point of application to the cores, the strands or wires are progressively formed into their ultimate formation upon the core so that they are assembled upon the core without

exerting any deleterious strains or pressures thereon.

Specifically, the invention provides a stationary combined core guide tube and wire preforming mandrel having a tip so shaped that each pair of wires during its travel
50 between its point of distribution and its point of application to the core is gradually preformed with the exact bends required therein before it passes onto and is supported by or assembled upon the pressboard core itself in its ultimate form, thereby eliminating any tendency of the wires through varying tensions thereon to distort the core during the stranding operation.

Other objects and advantages of this invention will more fully appear from the accompanying detailed description taken in connection with the accompanying drawing which illustrates one embodiment thereof, in which—

Fig. 1 is a fragmentary side view of the outlet end of a wire twisting or stranding machine embodying the features of this invention, showing a plurality of pairs of wires being served to a non-circular core;

Fig. 2 is a plan view thereof showing for the sake of clearness the serving of a single pair of wires;

Fig. 3 is an enlarged vertical section on the line 3—3 of Fig. 1, and

Fig. 4 is an enlarged detail section on the line 4—4 of Fig. 1.

It is believed that a better understanding of the improved method will be procured from a description of the improved apparatus, whereby the method may be practiced.

This invention will be described in connection with a wire twisting or stranding machine, such as is used in the manufacture of telephone cables. In order to simplify the disclosure of this invention only such elements of a stranding or serving machine have been shown as are necessary to a full and complete understanding of this invention. For a more complete illustration and description of a stranding or serving machine with which apparatus of the present invention is particularly applicable, reference may be had to Patent 1,579,769 to H. F. Jones, dated April 6, 1926.

Referring now to the drawing in detail the numeral 10 indicates a usual rotary dis-

tributor or guide ring provided, in the present instance, with twelve eyes or apertures 11, through each of which is threaded a pair of individually insulated twisted wires 12. 5 The distributor is adjustably carried upon a plurality of studs 13 rotatable with the stranding machine. In the operation of the machine each pair of the wires 12 is drawn from a freely rotatable supply spool (not 10 shown) carried upon a rotatable stranding drum (not shown). A telephone switch-board cable of the flat type is illustrated in the drawing as being formed, the pairs of wires 12 being stranded or twisted about a 15 thin flat pressboard core 15, which in the operation of the stranding machine is advanced toward the right as viewed in Figs. 1 and 2 at a predetermined rate, the core 15 passing along the axis of the machine upon 20 a stationary supporting plate 16 disposed below the core and extending from one end of the machine to the other and suitably supported from the floor or otherwise. Upon 25 passing from the right end of the machine, or the end which carries the distributor 10, the core 15 passes through an aperture 17 formed in the distributor 10. A polisher or compactor 18 of the usual type is provided with an aperture having a contour corresponding to the shape of the finished cable 30 which may be drawn therethrough by a usual capstan mechanism (not shown).

Fixed to the supporting plate 16 at its right end and extending between opposite 35 faces of the distributor 10 and compactor 18 is a combined core guide tube and wire pre-forming mandrel 20 embodying the features of this invention. The mandrel 20 comprises upper and lower complementary members 21 and 22, respectively, clamped together by a U-bolt 23, the lower member having an extension 24 upon its left end by means of which the assembled members 21 and 22 may be attached to the plate 16 by 40 screws. Extending longitudinally of the mandrel 20 throughout substantially the left half thereof as viewed in Figs. 1 and 2, which is circular in cross-section, is an aperture 27 which is rectangular in cross-section 45 and a trifle larger than the cross-sectional area of the pressboard core 15 which in the operation of the machine passes therethrough. The right half of each of the members 21 and 22 is sufficiently reduced in 50 width to cut away the opposite side walls of the aperture 27 as clearly shown in Fig. 2 between a point 28 and its extreme right end, thus reducing the width of the members to substantially the same as the core 15. In 55 addition, the members 21 and 22 are each tapered at their right ends in such a manner that they terminate in a point at opposite edges of the core 15 and upon opposite horizontal faces thereof and a comparatively 60 short distance from the left face of the com-

pactor 18 (Fig. 2). Thus it will be apparent that the core 15 is guided and supported along the greater portion of its area upon opposite horizontal faces thereof (Figs. 1 and 2) along the entire length of the mandrel 20, the opposed horizontal faces of the aperture 27 being continued throughout the length of the mandrel 20 right up to the extreme pointed right ends of the members 21 and 22. The operation of the serving apparatus hereinbefore described is as follows:

Referring particularly to Figs. 2 and 3 wherein it will be assumed that a single twisted pair of wires 12, for the sake of simplicity and clearness in illustrating the preforming operation, is to be served to the core 15, it will be observed that the wires are in actual contact with the lower side of the core 15 from the extreme pointed right end of the lower member 22 of the mandrel 20 to a point 30 at the left thereof. This distance embraces the greater portion of the tapered surfaces of the members 21 and 22 and along which the preforming of the wires occurs. Thus, in operation, assuming that the stranding drum (not shown) with the attached distributor 10 is revolving at a constant speed in a clockwise direction as viewed in Fig. 3 and that the core 15 is being moved longitudinally at a predetermined speed toward the right (Figs. 1 and 2), the wires 12 as they move to the right with the core 15 from the point 30 to the tip of the upper member 21 are pulled through their respective eye 17 of the distributor 10 and simultaneously moved clockwise or upwardly as viewed in Fig. 2. During this movement the wires are progressively formed into their ultimate formation upon the core, the actual bending of the wires taking place over the upper tapered end of the member 21 and the lower edge of the core which is supported directly above by the horizontal face of the upper member 21. Upon reaching the tip of the member 21 the wires have been completely formed around the edge of the core 15, the distributor then having revolved 180° and the wires having assumed the position indicated in dotted lines (Fig. 2) in contact with the upper face of the core 15. A continuation of the serving operation wraps the pair of wires over the lower tapered end of the member 22 and the upper edge of the core in a manner identical to that described in connection with the upper member 21. Upon the wires reaching the tip of either member 21 or 22 of the mandrel they have been completely preformed to fit around the edges of the core, free of any excess surplus at the bending areas so that they are completely assembled upon the core with the proper degree of tightness and without any sudden tightening thereon, thereby elimi- 125

nating any tendency of the wires through varying tensions thereon to distort the core, all tensions having been taken up during their engagement with the tapered ends of 5 the members 21 and 22 during their movement therealong from the points 30 to the tips thereof.

What is claimed is:

1. The method of serving a strand to a 10 non-circular shaped core, which consists in preforming the strand into its ultimate formation upon the core, and then assembling the thus formed strand upon the core.

2. The method of serving a plurality of 15 strands to a non-circular shaped core, which consists in progressively forming the strands into their ultimate formation upon the core, and simultaneously assembling the thus formed strands upon the core.

20 3. The method of serving a plurality of strands to a non-circular shaped core, which consists in distributing the strands from a plurality of points around the core, and preforming the strands into their ultimate formation upon the core.

25 4. The method of serving a plurality of strands to a non-circular shaped core, which consists in distributing the strands from a plurality of uniformly spaced points around the axis of the core, progressively forming the strands into their ultimate formation upon the core, and simultaneously assembling the thus formed strands upon the core.

30 5. The method of serving a plurality of strands to a non-circular shaped core, which consists in distributing the strands from a plurality of points around the core, pre- forming the strands into their ultimate formation upon the core, and causing a com- bined relative rotation between the points 35 and the core and a relative movement there- between along the axis of the core to

assemble the thus formed strands upon the core.

6. In a serving apparatus, means for 45 wrapping a strand around a non-circular shaped core, and means continuously engaging the strand during the serving operation for preforming the strand into its ultimate formation upon the core. 50

7. In a serving apparatus, means for distributing a plurality of strands from a plurality of points around a non-circular shaped core and wrapping them therearound, and means continuously engaging the strands 55 during the serving operation for progressively forming the strands into their ultimate formation upon the core.

8. In a serving apparatus, means for distributing a plurality of strands from a plurality of points around a longitudinally moving non-circular shaped core and wrapping them therearound, and a hollow mandrel, the outer surface of which is continuously engaged by the strands during the serving operation for preforming the strands into their ultimate formation upon the core, the core moving along the axis of the mandrel. 60

9. In a serving apparatus, means for distributing a plurality of strands from a plurality of points uniformly spaced around the axis of a longitudinally moving non-circular shaped core and wrapping them therearound, and stationary tapered means continuously engaging the strands during the serving operation for progressively forming the strands into their ultimate formation upon the core. 70

In witness whereof, I hereunto subscribe 80 my name this 1st day of October, A. D. 1926.

HENRY ROGERS MASSINGHAM.
